(57) **CLAIM**

The ornamental design for the partitioned food service assembly, as shown and described.

DESCRIPTION

FIG. 1 is a top view of a partitioned food service assembly comprising a tray a nesting partitioned dish, and a cover; FIG. 2 is a side elevational view, the opposite side view being a mirror image thereof;

FIG. 3 is an end elevational view, the opposite end view being a mirror image thereof;

FIG. 4 is an enlarged sectional view as taken at line 4—4 in FIG. 1; and,

FIG. 5 is a top perspective view illustrating the individual members comprising the assembly.
